[57] CLAIM

The ornamental design for modular telephone stand assembly, as shown and described.

DESCRIPTION

FIG. 1 is a right side, top and front perspective view of a modular telephone stand assembly showing our new design;

FIG. 2 is a top plan view thereof;

FIG. 3 is a front elevational view thereof;

FIG. 4 is a right side elevational view thereof;

FIG. 5 is a rear elevational view thereof;

FIG. 6 is a left side elevational view thereof; and

FIG. 7 is a bottom plan view thereof.

The broken line showing of a cord in FIG. 1 and a handset in FIGS. 1-7 is for illustrative purposes only and forms no part of the claimed design.

FIG. 1.

FIG. 2.

FIG. 3.

FIG. 4.

FIG. 5.

FIG. 6.

FIG. 7.
